United States Patent Office

Des. 205,345
Patented July 26, 1966

205,345

PIN CUSHION

Garvie J. Noe, 11300 St. Charles Rock Road,
Bridgeton, Mo.

Filed Feb. 1, 1966, Ser. No. 870

Term of patent 7 years

(Cl. D3—19)

FIG.1

I claim:

The ornamental design for a pin cushion, as shown and described.
